STIRRUP CONSTRUCTION

Samuel Klein, Chicago, Ill.

Application February 11, 1929, Serial No. 339,196

6 Claims. (Cl. 72—122)

My invention relates to improvements in stirrup constructions, and it consists in the combinations, constructions, and arrangements herein described and claimed.

5 An object of my invention is to provide a stirrup construction of the type adapted for concrete reinforcing in building construction and which has novel means whereby the units may be collapsed into a compact form.

10 A further object of my invention is to provide a device of the type described which has novel means for centering the unit in the desired position between the pans upon the form.

15 A further object of my invention is to provide a device of the type described which has novel means for readily positioning a plurality of stirrups in the desired position.

20 A further object of my invention is to provide a device of the type described which has novel means for correctly positioning the reinforcing irons or bars.

25 Other objects and advantages will appear in the following specification, and the novel features of the invention will be particularly pointed out in the appended claims.

My invention is illustrated in the accompanying drawing forming part of this application, in which

30 Figure 1 is a side elevation of one of the units of my device,

Figure 2 is an end elevation of the unit as positioned upon the form,

Figure 3 is a section along the line 3—3 of Figure 1,

35 Figure 4 is a top plan view of the unit shown in collapsed position,

Figure 5 is a diagrammatical illustration of the device as applied to the form, and

Figure 6 is another form of connecting the 40 stirrups to each other.

Fig. 7 is a front elevational view of an end stirrup as used at the left hand side of the device of Fig. 1, part being broken away.

Fig. 8 is a front elevational view of an end stirrup as shown at the right hand side of the device of Fig. 1, part being broken away.

In carrying out my invention I provide a pair of spaced-apart retaining members 1 which have stamped-out lip portions 2 at spaced-apart positions therein. A pair of spacing and retaining members 3 are also provided with stamped-out lip portions 4 at spaced-apart positions. The spacing members 3 are provided with outwardly extending integral arm portions 5 for a purpose 50 hereinafter described.

A plurality of substantially U-shaped stirrups 6 is provided with outwardly extending end portions 7. Desired groups of the lips 2 and 4 may be bent around the stirrups 6 for pivotally securing the stirrups to the members 1 and 3 as 60 illustrated in Figures 1 and 3.

Supporting end stirrups 8 and 9 are provided with retaining lugs or portions 10 adjacent the upper ends thereof, and spaced-apart retaining lugs or portions 11 near the lower ends thereof. 65 Groups of the members 2 may be bent around the stirrups 8 and 9 about the lugs 10 for pivotally connecting the stirrups 8 and 9 to the retaining members 1. Groups of the lips 4 may be bent around the stirrups 8 and 9 between the 70 lugs 11 for pivotally connecting the stirrups 8 and 9 to the spacing members 3. The stirrups 8 and 9 are provided with upwardly bent portions 12 which form supporting legs 13. The connecting portions 14 of the stirrups 8 and 9 are bent 75 upwardly at the centers thereof as illustrated in Figure 2. The connecting portion 14 in association with the mechanism 13 may be defined as a chair. The upper ends of the stirrups 8 are bent inwardly as illustrated at 15 in Figure 2. 80 The upper ends of the stirrups 9 are bent outwardly to conform to the upper ends of the stirrups 6.

From the foregoing description of the various parts of the device, the operation thereof may be 85 readily understood. The units may be disposed in the collapsed form prior to their being assembled upon a form. In Figure 2, I have shown a form illustrated in dotted lines at 16. The ordinary U-shaped pans are shown in dotted lines 90 at 17 as they are mounted upon the form. In assembling the units, they are first adjusted to their open positions and then placed upon the form 16. The units may be readily adjusted to their open positions by moving the members 1 or 95 3 away from each other or by swinging one of the various stirrups about its pivot. The arm members 5, as they project outwardly, tend to space the unit centrally between the pans 17. When placing the reinforcing bars, indicated in 100 dotted lines at 18 in Figure 2, between the pans 17, they may be disposed upon the cross members 14 and in so doing they will be positioned one at each side of the stirrups, as illustrated in Figure 2. These bars will be retained in this position due to the shape of the cross members 14.

If it is desired to place only one bar upon the cross members 14 for a certain construction, the cross members 14 may be bent downwardly so as to retain the bar at the center thereof. 110

In Figure 5, I have illustrated a plurality of units disposed end to end and have illustrated the manner in which the reinforcing bars 18 may extend over the inwardly projecting end portions 15 of the stirrups 8 and then extend downwardly and rest upon the cross members of stirrups 6.

With this construction a plurality of stirrups when not in use may be collapsed into a compact form, yet when desired to be used the stirrups 10 may be readily and simultaneously disposed in the desired position. The arms 5 will prevent the units from being displaced when the concrete is poured over the pans 17 and upon the form 16.

In Figure 6, I have shown another means 15 whereby the members 1 and 3 may be connected to the stirrups 6, 8, and 9. In Figure 6 the members 1 and 2 are provided with openings 19 through which the stirrups 6, 8, and 9 may extend so that the members 1 and 2 will be positioned 20 as indicated. The members 1 and 3 may be held in the desired position by welding lugs 20 to the stirrups for supporting these members.

I claim:

1. A stirrup construction comprising a plurality 25 of supporting members, a plurality of stirrups loosely connected with said supporting members, and an end stirrup loosely connected with said supporting members and being upwardly bent to form an integral chair portion providing for the spaced positioning of reinforcing rods.

2. A stirrup construction comprising a plurality 30 of supporting members, a plurality of stirrups loosely connected with said supporting members, and an end stirrup loosely connected with said supporting members and being provided with a chair portion, certain of said supporting members being provided with spacing portions, said chair portion being formed to provide spaced positioning and supporting means for reinforcing 40 means.

3. A stirrup construction comprising a plurality 45 of supporting members, a plurality of stirrups

loosely connected with said supporting members, and end stirrups loosely connected with said supporting members and being bent to form integral chair portions comprising downwardly extending legs and seats disposed in a plurality of elevations 80 for reinforcing bars.

4. A stirrup construction comprising a plurality 85 of supporting members, a plurality of stirrups connected with said supporting members, and end stirrups connected with said supporting members and being provided with chair portions, said stirrups being provided with laterally projecting portions and one of said end stirrups being provided with laterally projecting portions arranged oppositely with respect to said first-named laterally projecting portions.

5. A collapsible stirrup construction comprising 90 a plurality of supporting members, a plurality of stirrups pivotally connected with said supporting members and being provided with bent portions for spacedly positioning a plurality of reinforcing rods, certain of said supporting members being provided with spacing means for centering the entire stirrup construction intermediate a pair of form members.

6. In a collapsible stirrup construction the combination of pairs of supporting members having integral bent lips struck therefrom at intervals along the length thereof, stirrups comprising 105 spaced arms, each arm of each stirrup being definitely and pivotally mounted by corresponding lips on certain pairs of said supporting members, the stirrups thus connected serving in turn to constrain said pairs to certain positions, integral means on certain supporting members to space 110 the device from cooperating mold forms and integral bent portions on certain of said stirrups providing chairs for reinforcing rods, those portions of the stirrups beneath the chairs providing legs whereby the device is spaced from a soffit. 115
